US00D621274S

(12) **United States Design Patent**
Bouthillon et al.

(10) **Patent No.:** **US D621,274 S**
(45) **Date of Patent:** **** Aug. 10, 2010**

(54) **CONTAINER**

(75) Inventors: **Cristina Bouthillon**, Paris (FR);
Jacques Lalanne, Compiègne (FR);
Yves Guislain, Les Molières (FR)

(73) Assignee: **Colgate-Palmolive Company**, New York, NY (US)

(**) Term: **14 Years**

(21) Appl. No.: **29/321,722**

(22) Filed: **Jul. 22, 2008**

(30) **Foreign Application Priority Data**

Jan. 23, 2008 (EM) 000867288-0001

(51) **LOC (9) Cl.** **09-01**

(52) **U.S. Cl.** **D9/543**; D9/541; D9/551;
D9/556

(58) **Field of Classification Search** D9/685,
D9/516, 522-523, 530, 541-543, 549-552,
D9/563-565, 571, 575; 215/382-384; 220/675
See application file for complete search history.

(74) *Attorney, Agent, or Firm*—Amy M. Fernandez

(57) **CLAIM**

The ornamental design for a container, as shown and described.

DESCRIPTION

FIG. 1 is a perspective view of the container of our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the drawing views are included for the purpose of showing environmental structure that forms no part of the claimed design.

1 Claim, 6 Drawing Sheets
